UNITED STATES PATENT OFFICE.

PATRICK A. MEEHAN, OF BROOKLYN, NEW YORK.

SAFE.

1,164,951.

Specification of Letters Patent. Patented Dec. 21, 1915.

Application filed August 4, 1913. Serial No. 782,861.

To all whom it may concern:

Be it known that I, PATRICK A. MEEHAN, a citizen of the United States, residing in the borough of Brooklyn, county of Kings, city and State of New York, have invented 5 certain new and useful Improvements in Safes, of which the following is a specification.

This invention relates to safes, and aims 10 to provide improvements therein.

Safes are usually forcibly entered by boring a hole in the outer shell of the safe, adjacent the lock, inserting an explosive therein, as nitroglycerin, and exploding the same, or by pouring nitroglycerin in the 15 cracks around the door, and blowing the door off by exploding the nitroglycerin. In breaking into a safe, however, it is necessary that the safe be capable of being 20 worked upon, and particularly is this true in boring a hole therein, where it is necessary to have a firm support for the boring tool. Safes are susceptible to being bored into, and sometimes susceptible to having 25 nitroglycerin poured into cracks therein, and it is often possible to support a boring tool against a wall or other stationary part of the building wherein the robbery is being carried out, or the boring tool may be supported by a chain passing around the safe. 30

The present invention provides a safe which avoids the foregoing objections existing in ordinary safes, and which it is impracticable or impossible to operate upon, 35 particularly with boring tools. This is accomplished by providing means for keeping the safe, or an enveloping sheath, in motion.

The invention also preferably comprises means for preventing a person from following the movements of the safe, or the safe 40 is so located as to accomplish the same thing.

Several embodiments of the invention are illustrated in the accompanying drawings, 45 in which—

Figure 1 is a front elevation of one embodiment of the invention; Fig. 2 a front elevation of another embodiment; Fig. 3 a front elevation of a third embodiment; Fig. 4 a front elevation, with parts in section of 50 another embodiment; Fig. 5 a front eleva-

tion with parts in section, of another embodiment; and Fig. 6 a sectional view of still another embodiment.

Referring to Figs. 1, 2, 3 and 6 of the 55 drawings, numeral 1 designates any suitable safe, and 2 means for keeping the same in motion, the safe being rotatably mounted in suitable bearings 3.

The safe 1 may be of the usual square or 60 rectangular shape, as shown in Fig. 1, or cylindrical, as shown in the remaining views, or, in fact, any other desired shape.

The means 2 for keeping the safe in motion is preferably an electric motor supplied 65 with current from any suitable source, but preferably from a reliable central station.

By reason of the movement of the safe a person desirous of breaking into the same will find it impracticable or impossible to 70 work on the same, and consequently impracticable or impossible to accomplish his purpose of breaking into the same. The speed of rotation can, of course, be varied as may be desired. Moreover, the obvious difficulty of working on the safe, and the uncertainties of what may be connected to the safe, will deter many who might otherwise attempt to break in. Furthermore, by locating the safe in a window, or other prominent place, its motion will attract the attention of passers by, and will be an indication that its contents are intact. 75

Indicating means may also preferably be provided for giving a positive indication of 80 the movement of the safe. As shown in Figs. 1 and 2, this means may be in the form of a light 5 carried on the body of the safe, which light sends out a beam of light each time it passes a window or the like. As 85 shown in Fig. 3, this means may be in the form of a bell 6, which is struck by a striker 7 which is actuated by a projection on the safe each time the safe turns around. As 90 shown in Figs. 3 and 6, this means may be 95 in the form of a street sign 10, secretly connected to the safe, and intermittently illuminated, as by means of a commutator 11. In Fig. 3 current is supplied to the sign through a conductor 12, connected to one of 100 the motor leads and to the two brushes of the commutator, and a conductor 13 con-

- 5 nected to the other motor lead. In Fig. 6, current is supplied to the sign through a conductor 15 connected through a brush 16 to a conductor ring 17 on the under side of the safe and connected by a conductor 18 through the brushes of the commutator 11 with one of the motor leads, and through a conductor 19, through brush 20 and conductor ring 21, to the other motor lead.
- 10 10 Means are also preferably provided for preventing a person following the movements of the safe, and for preventing one from working upon the top of the safe. For the purpose, as shown in Fig. 2, the safe 15 may be located in a niche or recess 25 in a wall, partially surrounding and extending somewhat over the axis of rotation of the safe. As shown in Fig. 3 a lattice-frame 26 or the like may be fixed so as to stand close to one 20 side of the safe and over the axis of rotation. The lattice-frame is preferably wired and connected to a closed circuit alarm 27 situated in any desired locality or station. In either of these forms, a person attempting to follow the rotations of the safe will either run into the lattice-frame, breaking the same and giving an alarm, or be swept aside by the wall in which the safe is em- 25 bowered.
- 30 30 Means are preferably provided for indicating any change in the motion of the safe, as might occur by reason of an attempt being made to break into it, or to break the circuit from which the current is derived for 35 energizing the motor. As shown in Figs. 3, 4 and 6, this means may comprise an electric bell 30 set in operation by over-load and under-load cut-outs 31 and 32 in one of the 40 motor leads, which act upon one or other of the contact devices 33, 34, to complete a circuit through the bell.
- 45 In Fig. 4, the safe 1 is shown as stationary, being mounted on a suitable pedestal 40. 41 designates a sheath surrounding the safe, and rotatably mounted, as in a bearing 42 attached to the ceiling of the room in which the safe is located. The sheath may be rotated around the safe by suitable means, as a motor 2' similar to the motor 2 for rotating 50 the safe 1 in Figs. 1, 2, 3 and 6. A means, similar to that illustrated in Fig. 3, may be provided for giving an alarm whenever the motor 2' is tampered with. The means comprises over-load and under-load cut-outs 31', 32', in one of the motor leads, co-operating 55 with contact devices 33', 34', in circuit with an electric bell 30'. The safe is preferably wired on its exterior, as shown at 44, and the wires connected to a closed-circuit alarm 60 45. The sheath 41 after the safe is closed, is kept rotating. If a burglar should stop the sheath from rotating, or disconnect the sheath from the motor 2', the speeding up or slowing down of the motor would oper-

70 ate one of the cut-outs 31', 32', and actuate 65 the alarm 30. If a person should bore through the sheath 41, on reaching the inside of the sheath, the boring tool would come into contact with one of the wires 44 and operate the alarm 45.

75 In Fig. 5 a construction similar to Fig. 4 is shown. In this construction, the motor 2' is shown as located inside the sheath, on top of the safe, and the bearing 42' for the sheath also inside of the sheath on the motor 75 spindle.

80 In Fig. 6 the motor 2 is shown as located inside of the safe. Current is supplied to the motor through brushes 61, 62 and conductor rings 21, 22, on the under side of the 80 safe. The motor has an alarm device, comprising over-load and under-load cut-outs in one of the leads thereof, similar to that shown in Figs. 3 and 4.

85 While I have shown and described several embodiments of the invention, it is not to be understood as limited thereto, as the invention is capable of receiving a variety of mechanical expressions, and many modifications and changes may be made in the 90 embodiments shown without departing from the spirit of the invention.

95 What I claim is:—

1. In combination, a safe, and automatic means for keeping said safe in motion, the 95 manner of movement as regards speed and continuity being such that during periods in which the safe is to perform its safeguarding function forcible entry into the safe is rendered more difficult than in a 100 state of rest.

2. In combination, a safe, automatic means for keeping said safe in rotation during periods in which the safe is to perform its safeguarding function, whereby the safe is 105 additionally secured by its motion against forcible entry, and a stationary part in proximity to said safe.

3. In combination, a safe, automatic means for keeping said safe in rotation during periods in which the safe is to perform its 110 safeguarding function, whereby the safe is additionally secured by its motion against forcible entry, and a part in proximity to said safe extending over the axis on which 115 said safe turns.

4. In combination, a safe, a part in proximity to said safe, said safe and part having relative motion, and automatic means for producing such motion. 120

5. In combination, a safe, a sheath surrounding said safe, said safe and sheath having relative motion during periods in which the safe is to perform its safeguarding function, whereby the safe is additionally secured by its motion against forcible entry, and automatic means for producing such motion. 125

6. In combination, a safe, and automatic electrical means for keeping said safe in motion, the manner of movement as regards speed and continuity being such that during 5 periods in which the safe is to perform its safeguarding function forcible entry into the safe is rendered more difficult than in a state of rest.

In witness whereof, I have hereunto signed my name in the presence of two sub- 10 scribing witnesses.

PATRICK A. MEEHAN.
